(57) CLAIM

An ornamental design for a hand tool, as shown and described.

DESCRIPTION

FIG. 1 is a front perspective view of a new design for a hand tool that shows an ornamental gripping portion on a handle of the tool.

FIG. 2 is a front view thereof;

FIG. 3 is a rear view thereof;

FIG. 4 is a left side view thereof;

FIG. 5 is a right side view thereof;

FIG. 6 is an enlarged top plan view thereof; and,

FIG. 7 is an enlarged bottom plan view thereof.

The solid line showing illustrates the claimed features within the design for the claimed article of manufacture. The shading is provided to illustrate contour only and is not an indication of texture, gloss, etc.
